UNITED STATES PATENT OFFICE

2,446,137

CHIP TRUCK FOR SAWING AND OTHER MACHINES

Edward C. Krueger, Otsego, Mich., assignor to Hammond Machinery Builders, Inc., Kalamazoo, Mich., a corporation of Michigan

Application August 12, 1947, Serial No. 768,127

7 Claims. (Cl. 280—36)

1

This invention relates to improvements in chip truck for sawing and other machines.

The main objects of this invention are:

First, to provide a chip truck for sawing machines and other machines discharging chips or debris which is simple in structure and very easy to manipulate.

Second, to provide a truck or wheeled receptacle of this character in which the handle is telescopically collapsible with its parts on the outer side of the receptacle but at the same time does not objectionably project, and is guarded in collapsed position.

Third, to provide a truck of this character having a front wall which constitutes a closure for the opening in the wall of the pedestal adapted to receive the truck.

Objects pertaining to details and economies of the invention will appear from the description to follow. The invention is defined and pointed out in the claims.

A structure which embodies the features of this invention is clearly illustrated in the accompanying drawing, in which:

Fig. 1 is a front perspective view of a chip truck embodying my invention, its relation to the chambered pedestal of a sawing machine being illustrated. The sawing machine is shown by dotted lines and mainly in conventional form.

Fig. 2 is a fragmentary view showing the truck in side elevation position in the chamber of the pedestal, the pedestal being shown in vertical section.

Fig. 3 is an enlarged fragmentary view partially in vertical section showing the handle in fully extended position by full lines and partially extended by dotted lines.

Fig. 4 is an enlarged fragmentary view in section on line 4—4 of Fig. 2.

In the accompanying drawing 1 represents the pedestal of a sawing machine having an opening 2 in its front wall 3, the opening extending to the bottom of the pedestal. The machine illustrated is a trimming or sawing machine for electrotype plates. The sawdust, chips and debris are discharged downwardly into the pedestal. I am aware that it is old to provide chip trucks, as they are commonly designated, for use in this relation.

The chip truck of this invention comprises a receptacle designated generally by the numeral 4 and provided with wheels 5. The receptacle side walls 6 are provided with out-turned flanges 7 at their upper edges. The front wall 8 of the receptacle is designed to harmonize with the pedestal and extends laterally beyond the side walls as well as upwardly above the upper edges of the side walls and downwardly in front of the wheels in the form of an apron 9 to constitute a guard for the wheels, the front plate being of

2

such dimensions as to constitute a closure for the pedestal opening 2. The pedestal has inset flanges 10 around its top and side edges which serve as seats for the front wall 8.

5 The front wall is provided with holes 11 positioned in the laterally projecting portion of the front wall to receive the handle bars 12. These handle bars are provided with an integral cross piece 13 at their outer ends which constitutes a handle grip. The handle bars are slidable through the holes 11 to collapse at the outer sides of the side walls of the receptacle below the flanges 7 thereof. The angle slideway members 14 are secured to the side walls below the flanges 7 and preferably with their upper edges abutting the under sides of the flanges as illustrated in Figs. 2 and 4. These angle members are secured to the side walls by spot welds 15.

10 The slideways serve to support the handle bars 20 in horizontal collapsed position as shown in Fig. 2 with the grip disposed horizontally across the front of the front wall and spaced therefrom for grasping. The rear ends of the handle bars are curved upwardly at 15 so that when the handle bars are withdrawn they are supported in an upwardly inclined position for convenient grasping of the grip. In this position the truck may be either pulled or pushed by the handle and it will be observed that a push on the handle when 15 it is fully retracted serves to bring its angularly disposed end into clutching or binding engagement with the edges of the holes 11 so that the truck may be pushed by the handle, or, as stated, 20 may be pulled thereby. The pins 16 through the inner ends of the handle bars prevent their being withdrawn from the holes 11 and sustain the pulling load.

25 With the handle fully withdrawn the truck may be pulled or pushed about as desired and 30 may be pushed into the pedestal opening to position the front wall as a closure therefor. When the truck is positioned the handle may be swung downwardly to a horizontal position and pushed inwardly to collapsibly telescope the side bars of 35 the handle at the sides of the truck as shown in Fig. 2. When the handle is collapsed there are no projecting parts and there are no projecting parts when it is erected that are likely to interfere with the positioning of the truck within the pedestal. When the truck is positioned within the pedestal with the handle fully collapsed its grip 40 is disposed so that it may be conveniently grasped, and a continuous pull and upward swing brings it to position for removing the truck from the pedestal and manipulation to the dumping point by either pulling or pushing.

45 I have illustrated and described the invention in a practical commercial embodiment. I have not attempted to illustrate or describe other embodiments or adaptations which I contemplate 50 55

as it is believed this disclosure will enable those skilled in the art to embody or adapt my invention as may be desired.

Having thus described my invention what I claim as new and desire to secure by Letters Patent is:

1. In a chip truck for a machine having a chambered pedestal provided with a truck receiving opening in its front wall extending to the bottom thereof, the combination of a wheeled receptacle having side walls provided with out-turned flanges at their upper edges and a front wall extending laterally beyond the side walls and above the top thereof and below the bottom of the receptacle and constituting a closure for the pedestal opening, a handle comprising handle bars connected at their outer ends by a cross piece constituting a grip, the bars being slidably arranged through openings provided therefor in the front wall to telescope at the sides of the receptacle side walls, and angled slideways for said handle bars mounted on the side walls of the receptacle with their upper edges below said side wall flanges, said slideway members being adapted to support the handle in horizontal position when it is collapsed with its grip portion extending horizontally across the front wall, the handle bars having upwardly curved portions at their rear ends permitting the handle when extended to be swung to an upwardly inclined position for manipulation of the truck, said bars being provided with transverse retaining pins at their inner ends.

2. In a chip truck for a machine having a chambered pedestal provided with a truck receiving opening in its front wall extending to the bottom thereof, the combination of a wheeled receptacle comprising side walls and a front wall extending laterally beyond the side walls and above the top thereof and below the bottom of the receptacle and constituting a closure for the pedestal opening, a handle comprising handle bars connected at their outer ends by a cross piece constituting a grip, the bars being slidably arranged through openings provided therefor in the front wall to telescope at the sides of the receptacle side walls, and slideways for said handle bars mounted on the side walls of the receptacle, said slideway members being adapted to support the handle in horizontal position when it is collapsed with its grip portion extending horizontally across the front wall, the handle bars when extended being swingable to an upwardly inclined position for manipulation of the truck.

3. The combination of a portable receptacle having side walls provided with out-turned flanges at their upper edges and a front wall extending laterally beyond the side walls, handle bars provided with a grip at their outer ends, the bars being slidably arranged through openings provided therefor in the front wall to telescope at the sides of the receptacle side walls, and angled slideways for said handle bars mounted on the side walls of the receptacle with their upper edges below said side wall flanges, said slideway members being adapted to slidably support the handle in horizontal position when it is collapsed with its grip portion extending horizontally across the front of the front wall, the handle bars having upwardly curved portions at their rear ends permitting the handle when extended to be swung to an upwardly inclined position for manipulation of the receptacle, said bars being provided with transverse retaining pins at their inner ends.

4. The combination of a portable receptacle

comprising side walls and a front wall extending laterally beyond the side walls, handle bars provided with a grip at their outer ends, the bars being slidably arranged through openings provided therefor in the front wall to telescope at the sides of the receptacle side walls, and slideways for said handle bars on the side walls of the receptacle with their upper edges below said side wall flanges, said slideway members being adapted to slidably support the handle in collapsed position with its grip portion extending horizontally across the front of the front wall, the handle bars when extended being swingable to an upwardly inclined position for manipulation of the receptacle.

5. The combination of a wheeled receptacle having side walls provided with out-turned flanges at their upper edges and a front wall extending laterally beyond the side walls, handle bars provided with a common grip at their front ends slidably arranged through openings provided therefor in the front wall to telescope at the sides of the receptacle side walls, and angled slideways for said handle bars mounted on the sides of the receptacle with their upper edges below said side wall flanges, said slideways being adapted to support the handle in horizontal position when collapsed with its grip at the front of the front wall, the handle bars having angularly disposed portions at their rear ends adapted to be withdrawn through the front wall permitting the handle when extended to be swung to an upwardly inclined position for pushing and pulling manipulation of the truck, said bars being provided with retaining means preventing their withdrawal through the openings in the front wall.

6. The combination of a wheeled receptacle open at the top and comprising side walls and a front wall extending laterally beyond the side walls, handle bars provided with a common grip at their front ends slidably arranged through openings provided therefor in the front wall to telescope at the sides of the receptacle side walls, and slideways for said handle bars mounted on the sides of the receptacle adjacent the top thereof, said slideways being adapted to support the handle when collapsed with its grip at the front of the front wall, the handle bars being swingable to an upwardly inclined position for pushing and pulling manipulation of the truck.

7. The combination of a portable receptacle open at the top and comprising side walls, handle bars provided with a common grip, said bars being mounted on said receptacle to slidably collapse on the outer sides of the side walls and adjacent the top thereof, the receptacle having a front portion through which the handle bars extend, the bars being angled at their rear ends so that they are disposed in an upwardly inclined position when fully extended, the engagement of the handle bars with the receptacle being such that when in extended position the truck may be pulled or pushed thereby and when the handle is fully collapsed the grip is disposed at the front of the receptacle for grasping.
